MOLD-CAP FILLER BAR FOR INTERTYPE
CASTING MACHINES

Wellington Abbey George, Bellingham, Wash.

Application August 3, 1932, Serial No. 627,329

2 Claims. (Cl. 199—55)

My invention relates to improvements in mold-cap filler bars for intertype line casting machines and had for an object to provide a bar which when included in a particular mold cap of the said machine will enable the same to cast higher overhang on the type slugs than possible with the particular mold cap when the said bar is not included therewith.

Another object of my improvement is to make the said bar in different thicknesses to provide for a greater variety of heights of overhang with the same mold cap.

Another object of my improvement is to make the said filler bars of simple design and suitable for attaching in operative position without requiring additional parts for the mold caps or other parts of the machine.

Another object of my improvement is to retain the usual ability to cast smaller type on the slug 20 along with the larger type of the overhang.

Another object of my improvement is to shape the spring steel filler bar in a slight bow curvature which is straightened by being clamped in operative position on the mold body.

25 I attain these and other objects of my invention with the device illustrated in the accompanying sheet of drawing, which forms a part of this specification, in which Figure 1 is a front elevation view of a fragmentary part of the mold disc 30 of an intertype slug casting machine the remainder of which is broken away, Fig. 2 is a cross-section of Fig. 1 on a vertical medial plane and which also shows a cross-section of parts of the matrix holder of the machine, Fig. 3 is a plan view 35 of my mold-cap filler bar, Fig. 4 is an edge view of Fig. 3, Fig. 5 is a plan view of a type slug with small type thereon and also a type overhang higher than can be cast in the illustrated mold without using my mold-cap filler bar which is

40 shown in dotted outline disposed in operative relation therewith, Fig. 6 is an end elevation of Fig. 5, Fig. 7 is a plan view of a line of type too large for casting in the illustrated mold but which is introduced for comparison with the larger type 45 of Figs. 5 and 6, Fig. 8 is an end elevation of Fig. 7, Fig. 9 is a plan view of a line of type with overhang which may be cast in the illustrated mold, and Fig. 10 is an end elevation of Fig. 9.

Figs. 5—10 are drawn on a larger scale, and the 50 slugs illustrated in Figs. 5, 7 and 9 are shown as being broken away at each end thereof.

Similar characters refer to similar parts in the several views.

With more particular reference to the designated parts: On the frame 12 of the machine is

fastened stud 16 on which is mounted the mold disc 11 for revolution. The mold body 13 is fastened to the mold disc to provide the bottom wall of the mold 34 and it bears on the matrix 22 at $\alpha 13$. 14, 14 are pivot screws which engage the 60 eyes of oscillative clamping bolts 15, 15.

The pot-crucible mouth is shown at 17 and the pot jacket cover at 18. Both of these parts of the machine are stationary and are fastened to the framework thereof.

65 The first elevator jaws are shown at 19, 20 and they operate to retain the matrix in place against the mold body. One of the space bands is shown at 21, these being used to space the words in the type line. The matrix 22, having the type recess 70 $\alpha 22$ therein, bears against the front wall of the mold at the part $\alpha 13$ of the mold body 13, and also bears on the part $\alpha 23$ of the mold cap 23 and on the new mold-cap filler bar 25. The matrix type recess is adjacent the parts of the mold at 34 and 75 $\alpha 23$ and also adjacent the filler bar 25. Two mold liners 24, 24 are fastened to the mold body 13 to close the ends of the mold and determine the length of the slug cast therein.

80 The mold-cap filler bar consists of the bar 25, preferably of spring steel of rectangular cross-section, slightly bowed or curved as shown at $\alpha 25$. On each end of the bar is a lug 26 with a notch $\alpha 26$ therein to receive the oscillative clamping bolts whereby it is fastened to the mold cap. 85 The mold-cap filler bar is placed with its bowed-outward side $\alpha 25$ on the top of the bottom extension $\alpha 23$ of the mold cap 23 and is straightened by the nuts on the oscillative clamping bolts 15, 15 90 which are caused to enter the notches $\alpha 26$ by oscillation simultaneously with their adjustment to operative positions for clamping the mold cap 23 in operative position.

95 It thus appears that the mold-cap filler bar is placed and clamped in operative position without having made any changes in the disposition of the usual parts of the machine.

When the mold-cap filler bar is clamped against the part $\alpha 23$ as explained it contacts 100 therewith throughout its entire length, thus preventing the entry of molten type metal therebetween.

105 The line of type shown in Figs. 5 and 6 is assumed to have been cast in the mold 34 when the bar 25 formed a part thereof. As stated, the scale to which Figs. 5 and 6 are drawn is larger than that of Figs. 1 and 2. This line of type consists of slug 27 on which is small type 29, and the overhang 28 on which is larger type $\alpha 28$. The 110

relative position of the bar 25 to the type bar when the latter was in the mold is indicated in dotted outline in Figs. 5 and 6.

In Figs. 9 and 10 are shown two views of a line 5 of type assumed to have been cast in the mold 34 when the bar 25 was not used as a part thereof. This line of type consists of the slug 30 on which is small type *b*31, and the slug overhang 31 on which is larger type *a*31. The height of overhang 10 31 is the greatest which can be cast in the mold 34 without extending the walls thereof by using the bar 25. It is easily seen that letters *a*31 are smaller than are letters *a*28 although both are drawn to the same scale. This difference in 15 height of the letters favorable to those on the overhang 28 is attributable to the use of the mold filler bar 25 as explained above.

In Figs. 7 and 8 are shown two views of a line 20 of type which is larger than any that could be cast in mold 34 without using the bar 25, yet it is no larger than is the type *a*28 on overhang 28 which, as stated, could be cast in the said mold by using bar 25 as a part thereof.

It is now clear that the use of the mold-cap 25 filler bar 25 as an added part to the mold 34 makes possible the extended use of this mold beyond what could be cast therein, and that without using a different mold cap therewith. It is also clear that the bar 25 may be used for increasing the size of the mold and yet a slug with small letters cast thereon as well as the overhang with larger letters thereon be cast in the said extended mold.

That is, the use of the disclosed mold-cap filler 35 bar increases the range of the type which may be cast by the machine when using a particular mold cap, thus saving the expense of a part of the mold caps heretofore needed as supply parts of the machine.

40 The disclosed method of employing the mold-cap, filler bar has, in practice, been found to be

convenient. However, any other means of fastening the same in place of the same general character also is within the purview of this invention, and I desire to have it so understood.

Having thus disclosed my invention, what I 80 claim as new therein and desire to secure by Letters Patent is.—

1. In mechanism of the kind described, a mold body, a mold cap adapted for being releasably fastened to the said mold body, the first elevator jaws, 85 a matrix, having a type recess therein, retained in the said first elevator jaws operatively bearing on the said mold body disposing the said type recess adjacent the said mold cap and extended beyond the same, a mold-cap filler bar having its bottom and rear edge operatively disposed to rest on the said mold cap and on the said matrix adjacent the said extended portion of the matrix recess with its front face flush with the front face of the mold, lugs on the said filler bar, and fastening bolts and nuts bearing on the said lugs disposed to clamp the said mold cap filler bar and mold cap in operative position. 90

2. In mechanism of the kind described, a mold body, a mold cap adapted for being releasably fastened to the said mold body, the first elevator jaws, 100 a matrix, having a type recess therein fastened to the said first elevator jaws operatively bearing on the said mold body disposing the said type recess adjacent the said mold cap and extended beyond the same, a bow-shape mold-cap filler bar operatively disposed with its convex bottom and rear edge resting on the said mold cap and a plain side thereof on the said matrix adjacent the said extended portion of the matrix 105 recess with its front face flush with the front face of the mold, lugs on the said filler bar, and fastening bolts and nuts bearing on the said lugs disposed to clamp the said mold cap filler bar and mold cap in operative relation. 110
